UNITED STATES PATENT OFFICE.

ALEXANDER C. SLADKY AND JOSEPH SLADKY, OF MILWAUKEE, WISCONSIN.

OIL BURNER.

Application filed March 29, 1926. Serial No. 98,379.

This invention relates to oil stoves.

In oil stoves of the usual construction in which burners are supplied by oil from a reservoir through the medium of a main supply pipe, difficulty has been experienced due to the fact that the alignment of the burners in a horizontal plane is practically impossible with the heretofore known types of oil stoves.

For example, it is the usual practice to provide burners having open tops, such for instance, as that disclosed in the patent to Brennan No. 1,454,265 of May 8, 1923, and to supply these burners from a main supply pipe. Obviously, it is imperative to maintain the correct level of the oil under all conditions irrespective of irregularities in the floor level.

This invention is designed to overcome the difficulties noted above, and objects of this invention are to provide a novel form of oil stove in which the accurate alignment of the burners, when in operative position, is assured, and in which means are provided for taking care of any floor irregularities. For example, when it is considered that these burners are frequently placed in houses where irregularities in the floor exist, such for instance, as summer cottages, it is apparent that this invention fulfills a long felt want in this field.

Further objects of this invention are to provide a very simple construction which is easily produced and easily adjusted.

Embodiments of this invention are shown in the accompanying drawings, in which:

Figure 1 is a front elevation partly broken away of an oil stove.

Figure 2 is a diagrammatic view of a modified form of the invention.

Referring to the drawings, it will be seen that the oil stove is provided with the usual frame work 1 terminating in bottom feet. These feet are provided with fittings 2 each of which is equipped with a threaded aperture. An adjusting screw 3 is threaded through this aperture and carries a dish like foot 4 which may, if desired, be fluted at its edges as indicated on the right hand side of Figure 1 where the full line showing is disclosed. Preferably, these feet 4 have a dome like bottom.

The oil stove is provided with a supply tank 5 which may comprise a main inverted reservoir 6, preferably of glass. This reservoir is equipped with a flange 7 and a main

receiving cup 8 carries this flange and allows the neck 9 of the reservoir to be spaced a slight distance from the bottom of such cup. Preferably, apertures 10 are formed in the upper portion of the cup to provide free communication with air. Obviously, the fuel will discharge from the reservoir 6 until further flow is arrested by the oil coming to the bottom edge of the neck 9. This provides a constant oil level indicated at 11 in Figure 2 which is maintained by replenishing the oil from the reservoir 6 in an automatic manner.

A main supply pipe 12 extends horizontally through the stove and communicates with the bottom of the cup 8 by means of a restricted opening 8' as shown in Figure 2. This main supply pipe furnishes a plurality of branch pipes 13 which pass to the respective burners 14. These burners may be of any desired type, for instance, as disclosed in the above noted patent, and may be provided with adjustable burner drums 15. The burners 14 are adapted to be raised and lowered, such burners occupying the lowered positions when in operation. The purpose of the opening 8' of restricted size is to permit an adequate flow of oil to supply all of the burners. However, if for instance, the main tank 8 should become flooded as by the breaking of the container 6, a sudden rush of oil to the burners would be checked by the restricted opening 8'.

The supply pipe 12 extends horizontally through the stove and projects beyond the side thereof. It is provided at this point with a short standpipe or branch pipe 16 which carries a level indicating cup or drum 17 at its upper end. This drum is provided with an inwardly pressed bead 18 and with openings 19. A transparent cap 20 closes the upper end of this leveling drum or compartment.

It is to be noted that the bottom of the opening 19 is along the line 19', and this line is a slight distance below the top of the burners. In actual practice one-eighth of an inch has been found satisfactory for this spacing. Obviously, therefore, it is impossible to cause the burners to overflow for any reason whatsoever for the reason that the oil will find its way out through the openings 19 before overflowing the burners, and consequently, the safety of the stove is materially increased. It is to be understood also that the cup 17 may stop at the line 19' if desired, and may be open, although the form shown is prefer-

able. Further it is to be noted that although the cup 17 may be set within the outline of the stove if desired.

In operation, the stove is set up in the desired place, and the feet 4 are adjusted towards or from the legs until the oil comes level with the bead 18 as may be ascertained by looking downwardly through the transparent top 20. When this occurs the oil level is along the line indicated at 21 in each of the figures. This oil level is just right for each of the burners when they are in operative positions. Further, in making the adjustment, the oil level indicating compartment is at the extreme end of the pipe 12, and consequently, any inadvertent overflow during the initial adjustment of the stove will occur at this point and may be readily provided for by a suitable pan or bucket, thus preventing flooding of any portion of the stove or any of the burners even during this initial adjustment.

Although a specific type of burner has been described in connection with this invention, it is apparent that any suitable type can be used.

25 In the manufacture of this device, the burners and the oil leveling compartment are set by means of suitable gauges at a predetermined distance upwardly from the supply pipe 12. This is most easily accomplished 30 in the manufacture of the stove, and when they have been produced in this manner, it is a simple process to quickly level the stove so that the oil level is correct for each burner, thus securing the maximum efficiency for the 35 stove.

In practicing this invention, it may be desirable, under certain conditions, to provide the adjustment between the stove body and the oil system itself, instead of relying upon the adjustment of the entire stove. Figure 2 shows a scheme whereby this can be readily accomplished. In this figure, the same construction of oil system and burners is employed with, however, the difference that the oil system is movable relatively to the stove. For example, threaded pins or screws 22 may be screwed into suitable stationary portions 23 of the stove and may be provided with bearing portions 24 which support the horizontal pipe 12. Thus by adjusting the screws 21, it is a simple matter to secure the correct line up of each burner with reference to the oil level line 21.

It will be seen that a novel form of oil stove 55 has been provided by this invention in which means are furnished for insuring the correct leveling of the oil with reference to each of the burners so that the correct operation of the stove is assured.

60 It will be seen further that a very simple arrangement is employed for accomplishing this result.

Although the invention has been described

in considerable detail, such description is intended as illustrative rather than limiting as the invention may be variously embodied and as the scope of such invention is to be determined as claimed. 65

We claim:

1. An oil stove comprising a constant level supply tank, a supply pipe extending from said tank and having a plurality of upwardly extending branch pipes, a plurality of burners fed from said branch pipes, an oil level indicating compartment at the outer end of said supply pipe provided with an overflow, and means for adjusting the position of the supply pipe for causing the oil to occupy a predetermined level within the oil leveling compartment. 70 75

2. An oil stove comprising a main framework, a constant level tank associated therewith, a supply pipe extending from said tank through said stove, a plurality of upwardly extending branch pipes leading from said supply pipe, burners fed from said branch pipes, an oil level indicating compartment in communication with the projecting end of the supply pipe, and means for adjusting the position of the supply pipe to bring the oil to a predetermined level within said compartment. 80 85

3. An oil stove comprising a main framework, a constant level tank associated therewith, a supply pipe extending from said tank through said stove, a plurality of upwardly extending branch pipes leading from said supply pipe, burners fed from said branch pipes, an oil level indicating compartment in communication with the said supply pipe and located beyond one end of said framework, said framework having a plurality of supporting legs and adjustable feet carried by each of said legs. 90 95

4. An oil stove comprising a main framework, a constant level tank associated therewith, a supply pipe extending from said tank through said framework and projecting beyond one end thereof, an oil level indicating means carried externally of the framework by the projecting end of said supply pipe, said indicating means having a normal level indicating portion and having an overflow opening located thereabove, a plurality of burners fed from said supply pipe, said framework having a plurality of downwardly projecting legs, a plurality of feet carried by said legs and having a threaded adjustable connection with said legs. 100 105 110 115

In testimony that we claim the foregoing 120 we have hereunto set our hands at Milwaukee, in the county of Milwaukee and State of Wisconsin.

ALEXANDER C. SLADKY.
JOSEPH SLADKY.
